PARTITIONED BOTTLE CARRIER

Albert Wesselman, Cincinnati, Ohio

Application May 26, 1938, Serial No. 210,212

13 Claims. (Cl. 224—45)

This invention relates to containers for packaging bottles and the like and being of the general character shown in my Patent No. 2,171,615 and my co-pending applications, Serial No. 118,621, filed December 3, 1936 and abandoned, Serial No. 193,723 filed March 3, 1938 and Serial No. 200,952 filed April 8, 1938, and is a continuation in part of said applications.

An object of my invention is to provide a collapsible container for the packaging of bottles or a collapsible bottle carrier which when set up will provide a transverse and laterally partitioned structure into which bottles may be inserted through the top walls thereof.

Another object of this invention is to provide a bottle carrier structure which will have partitions provided between bottles in the same row as well as between bottles in an adjacent row, said partitions being integral with the prefabricated blank from which a carrier is fabricated.

A further object of the invention is to provide a carrier which will house a plurality of symmetrical units, each unit being spaced from adjoining units contained in said carrier, by a series of transverse and lateral partitions, said partitions being integral with the carrier structure.

A further object of the invention is to teach how to make a bottle carrier or the like having integral transverse and lateral partitions, said carrier having either a detachable handle or having a handle structure formed integral with the carrier structure.

Still a further object is to produce a bottle carrier which will securely retain the bottles housed therein even though said carton or carrier be turned on its side or end.

Still a further object is to provide a partitioned bottle carrier which will easily fit within a case lot shipping case or carton in which a plurality of bottle filled carriers are placed for the purpose of transportation by truck etc.

The foregoing and other objects are attained by the means disclosed herein and disclosed in the accompanying drawings, in which:

Fig. 1 is an end view of the assembled carrier comprising the invention, with bottles inserted.

Fig. 2 is a side elevational view of the carrier shown in Fig. 1.

Fig. 3 is a top plan view of the carrier shown in Fig. 1.

Fig. 4 is a plan view of an extended carrier or blank from which the carrier shown in Fig. 1 is made.

Fig. 5 is a perspective view of a modified form of an assembled carrier comprising the invention.

Fig. 6 is a plan view of an extended carrier or blank from which the carrier shown in Fig. 5 is made.

Fig. 7 is a perspective view of a second modi-

fied form of an assembled carrier comprising the invention.

Fig. 8 is a plan view of an extended carrier or blank from which the carrier shown in Fig. 7 is made.

Fig. 9 is an end view of a completed carrier showing the form in which such a structure is fabricated for shipment to the ultimate user or bottling establishments.

The carrier itself comprises a prefabricated blank of single thickness fibrous material such as cardboard or the like so joined to form an endless structure or body member, as hereinafter disclosed. Such a structure is completely assembled by the carrier manufacturer as a flat endless carrier (Fig. 9) which is shipped to the bottlers who set up such a flat assembled carrier as an extended carrier, the walls of which form a pentagon shaped body member or bottle receiving housing as shown in Fig. 1. Once set up as shown, bottles may be inserted into such an extended structure through the top walls as hereinafter more fully disclosed, and likewise removed therefrom.

The carrier is formed of a single, elongated or continuous piece of flexible sheet material. In referring thereto as continuous, it is intended to say that the sheet material is unitary but it is not intended to imply that the sheet material is initially endless; however, when portions thereof are joined or connected, a substantial portion of the sheet material is developed into an endless body or bottle housing member.

The bottles shown in Figs. 1, 2, and 3, each comprising a neck portion 10, an enlarged base portion 11, and an intermediate bulbous portion 12, are shown merely to illustrate how the carrier comprising this invention will accommodate symmetrical units having other than uniform cylindrical vertical side walls.

As shown in Fig. 4, a blank is fabricated to form a bottom section 13, having identical side walls 14 disposed on either side thereof. A plurality of spaced apertures 15 are stamped from said side walls, one such aperture being provided for each unit to be housed within the completed carrier. Suitable score lines 16 extending transversely of the blank set off the bottom section 13 from the apertured side walls 14 as shown.

Top members 17 are set off from each side wall 14 by means of suitable score or fold lines 18, the distance between pairs of adjacent score or fold lines 16 and 18 defining the height of the side walls.

Flaps 19 are provided in top members 17 in which all but the lower central sections 20 are severed whereby said flap may be folded inward about central scored section 20 as clearly shown in Fig. 1. Flaps 19 are also provided with lateral score lines 21 and 22 whereby the flap end sec-

tions 23 and 24 formed thereby may be turned at right angles to the central sections 25 thereof, said flap ends serving as compartment or pocket forming partitions between units in the same row, as more fully set forth in my co-pending application Serial No. 118,621. The bottle receiving opening or aperture provided incident to forming a flap 19 from each side wall or top member thereof, extends across the greater portion of the width of the side wall or top member, and lies beneath or below the finger openings provided by or in association with the handle member of the container or carrier. If the handle member is integral with the cardboard or sheet material, the handle member may be turned over or bent to substantially horizontal position at approximately the tops of any bottles resting on the bottom panel, as disclosed and explained in my Patent 2,171,615 and copending applications. Thus vertical stacking of loaded containers is possible for conserving floor or storage space, and also attaining an attractive and effective display of the grouped containers and their contents.

Each severed perimeter 26 resulting from the formation of flap members 19 is so proportioned and positioned relative to the side wall-top defining score line 18 as to furnish a positive bottle-neck contacting surface as clearly shown in Fig. 3. Such a bottle-neck contacting surface is essential to provide the anchorage or retaining force necessary to properly align each bottle as will hereinafter be more fully discussed.

As shown in Fig. 1 the carrier comprises a structure, the top members of which converge to form an apex A substantially below the level of the tops of the bottles B. The apex A is formed by folding top members 17 on transverse score lines 27 whereby two tabs of unequal length are provided. As shown in Fig. 4, a small tab 28 is provided adjacent the left hand side top member 17, while a large tab hereinafter referred to as transverse partition member 29 is provided adjacent the right hand side top member 17. It should be here noted that the tab and transverse partition member may be interchanged side for side, if desired.

The central portion of the apex forming score line 27 is slotted through longitudinally whereby a handle receiving cut 30 is provided, the length of said cuts being defined by the location of suitable circular cuts as 31.

A carrier is assembled by the carrier manufacturer from such a prefabricated blank by folding the transverse partition 29 inward on score line 27 so that said partition 29 will be interiorly disposed within the completed flat assembled carrier. The tab 28 is lapped over the upper outer edge of that top member which terminates in partition 29, as clearly shown in Fig. 9, and there permanently attached by adhesive or otherwise by the carrier manufacturer.

It should be noted that this type of bottle carrier structure is particularly adapted for glue assemblage because the tab 28 extends over apex A to lap over and extend down transversely over that portion of the top member which terminates in partition 29. The elements of the joint are so disposed whereby they will have a tendency to slide one upon the other under the weight of a loaded carrier, which relationship constitutes an ideal glue joint. Since a glue joint may be used the advantages inherent in such a joint viz., ease and speed of making, become a favorable factor whereby the assembly cost of the carrier is re-

duced to a minimum, being cheaper than a stitched or stapled joint.

Since a carrier must be glued with the adhesively coated surfaces in a flat, lapped relationship it becomes necessary to provide a transverse fold line 30 (Fig. 4) located in the side wall adjacent the tab 28 and disposed diagonally of the opposite side wall-top defining score line 18 whereby a prefabricated blank may be folded flat on fold lines 30 and 18 to expedite gluing. The completed assembled carriers are shipped to the various bottlers in this folded flat condition as clearly shown in Fig. 9.

The handle receiving slits 30 of an assembled carrier are aligned one below the other whereby a double thickness of stock extends outward from both ends of the handle receiving slits 30 to the outermost edge of the carrier structure transversely of the apex.

The assembled carriers are shipped flat to the ultimate users or bottlers who set up or extend the flat carriers and fill same with bottles in the following manner:

The opposite sides of the assembled but folded carriers are separated whereby a pentagonal sided structure results (Fig. 1). Such setting up of the assembled carriers may be expedited by means of a boxlike structure as disclosed in my copending application No. 172,883 filed November 5, 1937, issued Nov. 18, 1941 as Patent No. 2,263,411, which enables an operator to readily unfold an assembled carrier and which maintains the extended carrier in position for the insertion of bottles.

Once the carrier has assumed a pentagonal shape a handle 171 formed as disclosed in my copending application Serial No. 200,952, filed April 8, 1938, is adapted to be inserted upward through slit 30 in apex A so that the riser portions 172 of such handle will fall within the circular cuts 31.

When a handle is being inserted upward through slits 30 care should be exercised to make certain that the handle is inserted upward on that side of transverse partition 29 which is adjacent its associated top member or within the apex formed by the partition 29 and its associated top member. In this manner a double thickness of stock is provided along the load supporting termini 18 of said handle.

When the carrier is so set up or extended the transverse partition 29 extends downward from the apex A, and as shown in Fig. 1 it extends almost to the bottom member 13 whereby to function as a full length central partition member between the two transverse rows of bottles.

The flap portions 19 are then knocked or folded outward of the carrier structure on score lines 20 whereby a bottle receiving aperture is provided through each top member 17, each such aperture having a perimeter 26 (Fig. 3). The end bottles 40 and 41, and 140 and 141 are then inserted through the flap opening provided through the top member 17, the bottles of each row being separated by the transverse partition 28. As the center bottles 42 and 142 are inserted, the base portions of each bottle are brought upward beneath one of the flaps 19 whereby said flaps are folded inward of the carrier as the center bottles 70 are further inserted. The flap ends 23 and 24 are forced about the base portions of the bottles 42 and 142 as said flap ends are passed over the bulbous portion of the end bottles 40 and 41 and 140 and 141 respectively, until said flap ends have 75 been folded entirely within the carrier so as to

extend centerward on either side of the center bottle as shown in Figs. 1, 2, and 3. The center bottles are inserted simultaneously one from either side of the carrier, and by reason of the transverse partition the base portions of each bottle are easily caused to slip into place coming to rest on the bottom 13.

Such a transverse partition as 29 effectively prevents sanding of the bottles at the bulbous and base portions, and since said partition is fixed relative to the carrier structure, it acts as a bottle guide when the bottles are being inserted. Further, such partition enables an operator to insert bottles faster than were such a partition not present because as pairs of bottles are inserted, one from each side, the bases of the bottles abut the smooth wall of the partition down which they easily slip into position, as contrasted with the conditions encountered where such a partition is not present in which the butt of one bottle is caused to pass down the side of one bottle of the pair already positioned in the other row.

Lateral partitioning is effected by means of the flap ends 23 and 24 which separate bottles of the same row as shown in Figs. 1, 2, and 3.

Each bottle is securely held within an extended carrier by reason of the fact that the transverse partition and the perimeters 26 of top member of the carrier structure exert an outward force on the bottles whereby the base portions of each bottle are snugly seated within the spaced apertures 15, the transverse partitions performing the dual function of physically separating the bottles of each row and of forcing said bottles outward against the side walls. The perimeter 26 functions to position the top portion of each bottle so that the base of each bottle will be properly aligned relative to the transverse partition and the wall aperture 15.

It should be noted that a direct vertical pull is exerted by the load bearing termini 70 upon the uncut portions of apex A on either side of through slits 30. The load of a filled carrier is transmitted from the base 13 through side walls 14 to the uncut portions of said apex through the bearing strap C which comprises the strip of stock in the top members between the outer edges of the flaps 19 and the adjacent outermost edges of the carrier. A certain part of the load is also transmitted to the apex through the transverse partition against either side of which the bottles are tightly pressed when such a loaded carrier is lifted by means of a handle.

If desired, the transverse central partition member may be terminated at a point somewhat below the bulbous portion of the bottles whereby the transverse partitions will not act to separate the base portions of opposed bottles in each of the two transverse rows.

A carrier made as indicated in Figs. 1 to 4 inclusive, is quite compact and whether a detachable handle is used or not such a filled carton will very readily lend itself for stacking purposes, as more fully explained in my co-pending application Serial No. 200,952, filed April 8, 1938. Due to the novel design and compactness of the carrier herein disclosed a lighter or less expensive cardboard stock may be used from which to fabricate such carriers.

Such a handle as disclosed in Figs. 1, 2, and 3, is adapted to rest upon the bulbous portions of adjacent bottles when in a "retracted" position as more fully disclosed in my aforementioned co-pending patent application Serial No. 200,952.

A modified form of carrier having integral

transverse and lateral partitions is illustrated in Fig. 5, said carrier being formed with an integral handle formed from one side of the carrier, the central transverse partition being formed integral with the other side of the carrier. Similar parts bear the same numerals on Fig. 6 as on Fig. 4. Score lines 50 determine the apex junction of the top member 17. One top member however, terminates in a handle member 51 having a suitable aperture 52 provided therein. The opposite top member terminates in a transverse partition member 53. A median score line 57 is provided transversely of the bottom for assembly purposes.

15 A carrier is factory assembled from such a prefabricated blank by folding the transverse partition 53 back on itself on suitable score lines 54 which are spaced a distance from the adjacent score lines 50 as to provide suitable space to provide a fastening area 55, through which suitable fastening means such as staples 56, or the like, may be inserted. Such an assembled carrier is shipped in a flat condition to the bottlers, the carrier being folded on base median line 51 and on apex A'.

20 A second modified form of carrier is shown in Fig. 7 in which similar parts bear similar reference numbers to those parts set out in Figs. 1 to 4 inclusive. Score lines 60 and 61 (Fig. 8) 25 determine the apex formed by the convergent top members 17. One top member 17 terminates in a suitable handle member 62 having a suitable hand opening as 63 provided therein. The second convergent top member 17 terminates in a transverse partition 64. Suitable bearing elements 65 and 66 are provided integral with said top member, being severed from the transverse partition member 64 by suitable through cuts as 67 and 68 and 69 and 70, whereby the partition 25 member 64 is attached to top member 17 along the central portion of the score line 61 between parallel bearing surface defining cuts 68 and 70. A median score line 72 is provided transversely of bottom 13 for assembly purposes.

30 A carrier is factory assembled from such a prefabricated blank by folding the bearing elements 65 and 66 under the convergent top member which terminates in handle member 62 and so that the transverse partition member 64 will extend downward into the interior of the carrier structure formed thereby. Suitable fastening means as staples 71, may be used to fasten the bearing surfaces 65 and 66 to the under side of the opposite top member, as clearly shown in Fig. 7. The assembled carrier is shipped in a flat condition to the bottlers where it is extended and filled with bottles.

35 From the foregoing it is apparent that I have provided an inexpensive bottle carrier having transverse and lateral partitions formed integral therewith, said carrier structure being assembled by the carrier manufacturer and shipped in a flat condition to the ultimate user. Said carrier being set up or extended by such ultimate user to form an open pentagonal ended carrier, bottles may be inserted into said extended carrier through the top members thereof.

40 It is to be understood that various modifications and changes in the structural details of the device may be made, within the scope of the appended claims, without departing from the spirit of the invention.

45 What is claimed is:

50 1. A container for the packaging of bottles or the like comprising a base, a pair of opposed side

walls attached to opposite edges of said base, a pair of upwardly convergent top members, one connected to the upper edge of each side wall, each top member having a flap formed therefrom, each flap having only the central portion of its lower edge attached along the upper portion of its respective side wall, movement of said flaps laterally relative to said top members providing bottle receiving openings in the top members, each of said openings extending across the greater portion of the width of the top members, said top members converging and joined to form an apex, the vertical distance from said base to said apex being substantially less than the overall height of any unit of merchandise to be housed within said container, one top member terminating in a transverse partition member folded interiorly of the container whereby to provide a transverse partition extending downward from the apex, said partition adapted to lie between adjacent rows of bottles aligned with and extending into the openings in the top members, and a handle connected to the container at the apex thereof.

2. A container for packaging bottles comprising a sheet of prefabricated fibrous material assembled to form a container structure comprising a base, a pair of opposed side walls, said side walls being extended upwardly to form a pair of integrally connected convergent top members, each top member having a flap formed therefrom and providing thereby a bottle receiving opening extending across the greater portion of the width of the top member, the perimeter of each flap being entirely severed from its associated top member except along the central portion of its lower edge which is attached to the upper edge of its respective side wall, said flaps being laterally scored so as to set off central and end portions adapted to be turned at right angles to said central section whereby to provide lateral partitions between adjacent articles of a row of articles disposed adjacent the same side wall of the container, a transverse partition member formed integral with and suspended from one top member whereby articles disposed in a row adjacent one side wall of the container are separated from those in a row adjacent the other side wall of the container.

3. A container package for packaging beverage bottles which have a neck and an enlarged base with an intermediate bulbous portion, said package comprising a sheet of prefabricated fibrous material, said sheet being scored transversely to form a bottom, a pair of opposed side walls, a pair of upwardly convergent top members extending from the sides and meeting at a top apex located below the level of the bottle tops, one top member being extended beyond the apex and turned downwardly between the side walls to terminate in a partition disposed transversely of the interior of the container, the second top member being extended beyond the apex to make connection with the other top member for forming a continuous or endless structure or body member, a handle for the body member, each top member having a flap formed therefrom, said flaps being scored laterally whereby to form central and end portions adapted to be turned at right angles to said central section when the flaps are turned downward, whereby to provide partitions disposed laterally of the container and extending between adjacent bottles, the downward turning of the flaps providing openings in the top members, each open-

ing providing at each of its opposite ends a bottle-neck positioning edge adapted to contact the neck of an adjacent bottle.

4. A container for the packaging of bottles comprising a base, a pair of opposed side walls attached to opposite edges of said base, a pair of upwardly convergent and connected top members each connected to the upper edge of a side wall, each top member having a bottle receiving opening formed therein and extending across the greater portion of the width thereof, the material removed from said openings being formed into flaps each having connection with the container and each flap being scored laterally whereby to provide partitions extending laterally of the container, said converging top members forming an apex intermediate and above the side walls of the container, and a handle for the container and extending upwardly from said apex.

5. A container for the packaging of bottles comprising a base, a pair of opposed side walls attached to opposite edges of said base, a pair of upwardly convergent top members each connected to the upper edge of a side wall each top member having a bottle receiving opening formed therein and extending across the greater portion of the width thereof, the material originally lying within said openings being developed into flaps, each having its lower edge hingedly connected to a side wall, said flaps being scored laterally whereby to provide partitions laterally of the container, said top members converging to form an apex, one top member being extended over said apex to terminate interiorly of the container whereby to form a transverse partition, the second top member being extended over said apex in a lapped relationship to the first top member transversely of the apex whereby a unitary structure is formed, said apex having a longitudinal slit extending centrally thereof whereby to provide uncut apex portions on either side of said slit whereby to accommodate a bodily displaceable handle insertable upwardly through said slit.

6. In a container for the packaging of bottles comprising a base, a pair of opposed side walls attached to opposite edges of said base, a pair of upwardly convergent top members extending from the side walls and meeting at an apex, each top member having a flap formed therefrom and having only the central section of its lower edge attached along the upper portion of its respective side walls, each top member having an aperture or opening formed therein and extending across the greater portion of the width of the top member, said flaps being scored laterally whereby to form central and end portions adapted to be turned at right angles to said central section whereby to provide opposed lateral partitions disposed interiorly of the container, one top member being extended downward from the apex terminating in a partition disposed intermediate and between the side walls, and extending lengthwise of the interior of the container and at right angles to the lateral partitions, the second top member being extended upward from the apex to form a handle portion, the two top members being connected adjacent the apex to form a unitary structure, said handle and partition being approximately coplanar and substantially integral whereby any load directed or impressed upon said partition is transmitted directly to said handle.

7. A paperboard container for the packaging of bottles, formed of a single continuous piece of sheet material and comprising a base, a pair of opposed side walls attached to opposite edges

of said base, a pair of upwardly convergent top members each connected to the upper edge of a side wall, each top member having a bottle receiving opening formed therein and extending across the greater portion of the width thereof, said top members converging to form an apex, one top member being extended downward of said apex to terminate interiorly of the container whereby to form a transverse partition substantially dividing the interior of said container into approximately equal and identical bottle receiving chambers, one each of which chambers being aligned with a bottle receiving opening and adapted to accommodate a plurality of bottles, the second top member being permanently fastened relative to the first top member whereby to form an endless bottle receiving body structure, and a handle at the apex of the container.

8. In a container for the packaging of bottles and the like, a body formed of paper board material or the like and including a bottom panel and side panels extending upwardly at opposite sides thereof, the upper portions of said side panels being connected to each other and being each provided in its upper portion with a bottle-receiving aperture spaced below the connection of said side panels, and each aperture extending across the greater portion of the width of the container, said apertures each being of a width no less than the diameter of any of the articles to be received by the container, a combined partition and stiffening member extending inwardly of the container from adjacent the connection of said side panels and adapted to cooperate with the conjoined side panels and with articles received between the side panels and lying on opposite sides of said partition and stiffening member, for bracing the portions of the material at the sides of the bottle receiving openings and for transferring some of the load of the carrier to those portions of the carrier disposed above said bottle receiving openings, and a handle for the container.

9. A container for the packaging of bottles and the like comprising a base, a pair of sides, one each attached to opposite edges of the base, a pair of top members each connected to the upper edge of a side, and converging to form an apex above the center line of the base, each top member having a perforation therein providing an included flap having its lower central edge only attached to the upper central portion of its respective side and along one edge of the perforation, each flap being turned downwardly inside and flatwise along the pair of sides and each flap having end portions turned centerward of the device along vertical lines of fold whereby to provide a series of compartments along the inner face of each of the sides.

10. A container for the packaging of bottles comprising a base, a pair of sides attached to opposite edges of the base and each having spaced pockets along its lower edge, a pair of top members each connected to the upper edge of a side, each top member having a flap formed therefrom and having its lower central edge only attached along the upper central portion of its respective side, each flap being turned downwardly between the pair of sides and each flap having its end portions turned centerward of the device along vertical lines of fold whereby to

provide a series of compartments along the inner face of each of the sides, a partition member between the inturned end portions of the flaps and a handle member extending upwardly from the top members and having an aperture therein for providing a finger receiving opening through the handle member, the base having a median score line extending transversely of the container.

11. A container for the packaging of bottles comprising a base, a pair of sides attached to opposite edges of the base, a pair of top members each connected to the upper edge of a side, each top member having a flap formed therefrom, each flap having its lower central edge only attached along the upper central portion of its respective side, each flap being turned downwardly between the pair of sides and each flap having its end portions turned centerward of the device along vertical lines of fold whereby to provide a series of compartments along the inner face of each of the sides, a partition member between the inturned end portions of the flaps, the base having a median score line extending longitudinally of the container, and a handle for the container.

12. A container for the packaging of bottles comprising a base, a pair of sides attached to opposite edges of the base and each having spaced pockets along its lower edge, a pair of top members each connected to the upper edge of a side, each top member having a flap formed therefrom, each flap having its lower central edge only attached along the upper central portion of its respective side, each flap being turned downwardly between the pair of sides and each flap having its end portions turned centerward of the device along vertical lines of fold whereby to provide a series of compartments along the inner face of each of the sides, a partition member between the inturned end portions of the flaps, the base having a median score line extending longitudinally of the container, and a handle for the container.

13. A pentagonal container for the packaging of bottles, comprising a single, continuous, elongated piece of paperboard sheet material having portions thereof fixedly attached together to provide an endless body having a plurality of parallel fold lines extending across the width thereof for providing a hollow pentagonal shaped container, one of the portions thereof disposed between an adjacent pair of fold lines constituting a base therefor, the portions thereof adjacent to and contiguous with the base constituting substantially parallel spaced side walls thereof and the remaining two portions providing an apex over said base and constituting top members thereof, said top members each having an elongated bottle receiving opening therein, said openings extending across the greater portion of the width of said top members, a portion of said sheet material extending through said apex and depending in substantial parallelism with the side walls and into the space between the side walls and approximately equally dividing said space into a pair of bottle receiving pockets disposed on opposite sides of said base, and a handle at the apex of the container.

14. A pentagonal container for the packaging of bottles, comprising a single, continuous, elongated piece of paperboard sheet material having portions thereof fixedly attached together to provide an endless body having a plurality of parallel fold lines extending across the width thereof for providing a hollow pentagonal shaped container, one of the portions thereof disposed between an adjacent pair of fold lines constituting a base therefor, the portions thereof adjacent to and contiguous with the base constituting substantially parallel spaced side walls thereof and the remaining two portions providing an apex over said base and constituting top members thereof, said top members each having an elongated bottle receiving opening therein, said openings extending across the greater portion of the width of said top members, a portion of said sheet material extending through said apex and depending in substantial parallelism with the side walls and into the space between the side walls and approximately equally dividing said space into a pair of bottle receiving pockets disposed on opposite sides of said base, and a handle at the apex of the container.
